METHOD OF MAKING AND ASSEMBLING A SLIDER
Louis H. Morin, 125 Beechwood Ave., Bronx, N.Y.
Filed Feb. 19, 1963, Ser. No. 259,613
6 Claims. (Cl. 29—408)

This invention relates to a method of making sliders used in conjunction with stringers of separable fasteners in coupling and uncoupling the scoops thereof. More particularly, the invention deals in a method of making sliders of this type and kind which will permit assembly of the scoops of the stringers with the slider, thereby eliminating conventional joining methods of assembling sliders with separable fasteners, so as to be able to permit for automation for this operation.

Still more particularly, the invention deals with a method of forming sliders of the character defined, wherein one or both walls of the slider include side flanges retaining the scoops in operative engagement with the slider when assembled therewith in accordance with my method.

The novel features of the invention will be best understood from the following description, when taken together with the accompanying drawing, in which certain embodiments of the invention are disclosed and, in which, the separate parts are designated by suitable reference characters in each of the views and, in which:

FIG. 1 is a side view of one form of slider made according to my invention, preparatory to assemblage of the slider with scoops of stringers and attachment of a pull therewith.

FIG. 2 is a plan view of the slider shown in FIG. 1, illustrating the cores used in formation of the slider, parts of the construction being broken away and in section.

FIG. 3 is a section on the line 3—3 of FIG. 2.

FIG. 4 is a partial section on the broken line 4—4 of FIG. 2 illustrating the slider shown in FIGS. 1 and 2.

FIG. 4a is a broken section substantially on the same line showing a modified form of slider.

FIG. 5 is a diagrammatic view illustrating the method of assembling the scoops with a slider, such as shown in FIGS. 1, 2 and 4 of the drawing; and

FIG. 5a is a view, similar to FIG. 5, showing the method of assembling scoops with a slider as shown in FIG. 4a.

Considering the slider as shown in FIGS. 1 and 2 of the drawing, the slider body consists of walls 10 and 11 joined and spaced at the wide end of the slider in a connecting frog or web 12, generally of the contour illustrated in dotted lines in FIG. 2. The wall 10 has side flanges 13, as clearly noted in FIG. 2, and one of which is partly shown in section in said figure. The wall 10 also has projecting from the outer surface thereof a yoke-shaped member or clambucket 14, in the rounded portion 15 of which the pivot of a pull is adapted to be retained by bending the sides 16 inwardly in final formation of the slider. No pull is shown, as it forms no direct part of this invention. In casting the slider, the wall 10 is also preferably formed with an aperture 17 for reception of a lock element commonly employed on a pull.

In casting the slider body, two cores 18 and 19 are employed, the core 19 having a long tongue portion 20, having a V-recess 21 in its free end in partial formation

2

of the web 12; whereas, the core 18 is recessed, as at 22, to receive the tongue 20, as clearly indicated by the sectional portions of the slider illustrated in FIG. 2 of the drawing. The two cores collectively form the channel or channels of the slider body and, considering FIG. 3 of the drawing, it will appear that the cores 18 and 19 have surfaces 18', 19' to form the wall 11 with outwardly flared sides, as indicated at 11' in FIG. 3 of the drawing.

This construction provides between 23 of the flanges 13 and the inner surface 24 of the offset walls 11' a clearance space sufficient for reception of scoops of a fastener stringer such, for example, as the scoop 25 on the stringer 26 illustrated in FIG. 5 of the drawing, in which figure the flare 11' of the wall 11 is indicated in dot-dash lines, preparatory to compressing 11' into its scoop retaining position, as shown in section in FIG. 5, this operation being performed by a punch 27 with the slider arranged upon a suitable support or anvil 28.

Considering the foregoing, it will be understood that the core 18 has a cross-sectional contour, such as illustrated in FIG. 4 of the drawing, in formation of the wall 10 and the wall 11 in its flared state. In this connection, the broken section line 4—4 is to be kept in mind.

In FIG. 4a and FIG. 5a, I have shown the formation of a modified form of slider, in which 29 is a wall, similar to the wall 10, 30 a wall, generally similar to the wall 11, with the exception that 30 includes a flanged side, as at 31, and at 32 is shown part of the connecting web.

In forming a slider such as shown in FIGS. 4a and 5a, a core, generally similar to the core 19, will be employed; whereas, a core, similar to 18, will be modified in contour and such a core is indicated, in part, at 33 in FIG. 4a of the drawing. This core is modified to the extent of forming the flange 31 and it will be apparent that a portion of the core 19 at the narrow end of the slider will be correspondingly formed. With this construction, the space between the inner edge 34 of the flange 31 and the edge 35 on the flange of the wall 29 will provide the admission passage for free positioning of a scoop, such as the scoop 25' of FIG. 5a, in the channels of the slider body, as diagrammatically illustrated, in part, in FIG. 5a; whereupon, a punch 27', similar to 27, in conjunction with 28', similar to 28, are utilized in compressing the wall 30 from the sectional position of FIG. 5a to the dot-dash position shown in said figure, as and when the scoop 25' has been positioned in the channel or channels of the slider body.

From a consideration of FIGS. 1, 3 and 4 of the drawing, it will be apparent that the flare of the wall 11 extends from sides of the web and from the central portion of the wall beyond the web, as indicated at 11" in FIG. 3 of the drawing.

From the foregoing, it will be apparent that, by initially forming the slider body with the walls in a flared or open position, the operation of assembling coupled stringers of a separable fastener with the slider is materially simplified and facilitates automation for this operation and the scoops of the stringers will be retained in proper operative position. As will be apparent, this would apply to sliders wherein flanges are employed on one wall only of the slider or wherein it is desirable to use flanges on both walls thereof. Further, with the present method, no pressure is required to distort the connecting web or frog of the slider body, as reforming or shaping is restricted primarily to the flared wall of the slider body.

Having fully described my invention, what I claim as new and desire to secure by Letters Patent is:

1. The method of forming a slider body to facilitate attachment of coupled stringers therewith and in compressing flared wall portions of the slider body in retaining the scoops of stringers against displacement from the slider body, which comprises casting a slider body having walls spaced and joined by a web at a wide end portion of the slider body with one wall flared with respect to the opposed wall to form wide admission passages at sides of the slider body for reception of scoops of separable fastener stringers, positioning the scoops of a pair of stringers in and between the walls of the slider body, and then compressing said flared wall to retain the scoops of the stringers against displacement from the slider body. 15
2. A method as defined in claim 1, wherein at least one wall of the slider body includes side flanges.
3. A method as defined in claim 1, wherein both walls of the slider body include side flanges.
4. A method as defined in claim 1, wherein the flare 20 of said one wall extends from sides of said web and the central portion of said wall.
5. A method as defined in claim 4, wherein at least one of the walls of the slider body includes side flanges, and said passages being formed between the side flanges 25 and central portion of said wall.
6. The method of forming a slider body to facilitate

attachment of coupled stringers therewith and in compressing flared wall portions of the slider body in retaining the scoops of stringers against displacement from the slider body, which comprises forming a slider body having walls spaced and joined by a web at a wide end portion of the slider body with one wall flared with respect to the opposed wall to form wide admission passages at sides of the slider body for reception of scoops of separable fastener stringers, positioning the scoops of a pair of stringers in and between the walls of the slider body, and then compressing said flared wall to retain the scoops of the stringers against displacement from the slider body.
